UNITED STATES PATENT OFFICE.

EDGAR H. BERRY, OF CHICAGO, ILLINOIS.

DESIGN FOR A GARMENT-HANGER.

48,852.

Specification for Design.

Patented Apr. 11, 1916.

Application filed February 3, 1916. Serial No. 76,059. Term of patent 14 years.

To all whom it may concern:

Be it known that I, EDGAR H. BERRY, a citizen of the United States, residing at Chicago, in the county of Cook and State of Illinois, have invented a new, original, and ornamental Design for Garment-Hangers, of which the following is a specification, reference being had to the accompanying drawing, forming part thereof.

Figure 1 is a face view of a garment hanger embodying my new design. Fig. 2 is a plan view of the same garment hanger.

I claim:

The ornamental design for a garment hanger, as shown.

EDGAR H. BERRY.

Witnesses:

H. N. SHAW,
D. A. BRADING.
